UNITED STATES PATENT OFFICE.

ANTON FLETTNER, OF BERLIN, GERMANY.

RUDDER.

Original application filed June 29, 1920, Serial No. 392,839, and in Germany September 22, 1917. Divided and this application filed July 9, 1927. Serial No. 204,517.

The present invention relates to the steering of water-borne vessels and more particularly to an improved rudder.

The large ships of today require large 5 rudders which are necessarily very heavy and a very large force is needed to move them, consequently, heavy and cumbersome steering engines are a necessary adjunct to any large steamer. These steering engines 10 consume a great deal of power and furthermore, with these steering systems a considerable time is needed to throw the rudder over completely. With the ordinary steering engine, about fifty seconds are required 15 to throw the rudder over. It is the object of the present invention to provide a rudder which will not only require less power in its operation, but which can be thrown over more rapidly.

20 The invention consists briefly in attaching to the main rudder an auxiliary rudder which is at the same time connected with the ship and in such a manner that the movements of the auxiliary rudder are dependent 25 upon those executed by the main rudder. The deflection of the main rudder will take place in the same manner as before but the deflection of the main rudder causing a deflection of the auxiliary rudder in such a 30 way that under the influence of the forces of flow acting thereon the deflection of the main rudder will now be facilitated by the action of the auxiliary rudder. In other words, while the main rudder is being 35 thrown over by the steering engine, the auxiliary rudder will be steering the main rudder in the same direction, (i. e. the auxiliary rudder will be displaced by the main rudder in a direction to facilitate the further oscillation of the main rudder). As a result of 40 the use of this auxiliary rudder, less power is needed in steering and the main rudder may be more rapidly thrown over.

45 Two preferred embodiments of my invention are shown diagrammatically by way of example in the accompanying drawings.

In the form of construction according to Fig. 1, the main rudder 3 is mounted on the ship 4 in any appropriate manner. The 50 steering mechanism is not shown as such mechanism is well known and does not form a part of this invention. At the rear edge of main rudder 3, an auxiliary rudder 5 is pivoted, so as to be freely movable around a pivot or shaft 6. The auxiliary rudder is

connected by means of a link 7, and a connecting rod 8, to a projection 9 on the hull of the ship 4. The link and connecting rod are so proportioned that when the main rudder is turned to starboard, the auxiliary 60 rudder is shifted to larboard and vice versa. The extent of the shift depends on the length of link 7, and connecting rod 8. The dimensions of these elements will depend on the size of the main rudder and may be easily 65 ascertained by any skilled mechanic under given conditions.

In the form of execution according to Fig. 2, the main rudder 3^a is mounted on the ship 4^a and the auxiliary rudder 5^a is pivoted 70 to the main rudder as before. Stationary sheaves 10, 11 are mounted respectively on the ship and the auxiliary rudder, and the auxiliary rudder is connected to the hull of the ship by an endless cable 12 carried by 75 sheaves 10, 11 so that when the main rudder is turned to starboard the auxiliary rudder will be turned to larboard and vice versa.

In both these illustrations, the automatic setting of the auxiliary rudder counter to 80 the deflection of the main rudder, effects an acceleration and facilitates the deflection of the main rudder.

This application is a division of my prior application, filed June 29, 1920, Serial No. 85 392,839 for a "Method and device for the steering of ships".

I claim:

1. In a water-borne ship the combination of a main rudder, an auxiliary rudder, means 90 connecting said auxiliary rudder with the main rudder and with the ship for turning said auxiliary rudder relatively to the main rudder in a sense to facilitate turning of the main rudder.

2. In a water-borne ship the combination of a main rudder, means for positively turning the main rudder, an auxiliary rudder connected with said main rudder near the rear edge thereof and connection between said 100 auxiliary rudder and said ship for turning said auxiliary rudder in a sense counter to that in which said main rudder is being turned.

3. In a water-borne ship, the combination 105 of a main rudder, an auxiliary rudder connected therewith and means linking the auxiliary rudder with the hull of the ship in such a manner that the steerman in deflecting the main rudder will at the same time dis- 110

place the auxiliary rudder in a direction to facilitate the further deflection of the main rudder.

4. In a water-borne ship the combination of a main rudder, an auxiliary rudder mounted on the main rudder near the rear edge thereof, means for positively turning the

main rudder, and means linking the auxiliary rudder with the hull of the ship whereby the auxiliary rudder is turned in one direction relative to the main rudder and thus assists in turning the main rudder. ¹⁰

In testimony whereof I affix my signature.

ANTON FLETTNER.
